UNITED STATES PATENT OFFICE.

EARL BLAINE SHERK, OF LEBANON, PENNSYLVANIA.

APPARATUS FOR CUTTING VALVE FACES.

Application filed December 21, 1920. Serial No. 432,354.

To all whom it may concern:

Be it known that I, EARL B. SHERK, a citizen of the United States, and a resident of Lebanon, in the county of Lebanon and State of Pennsylvania, have invented a new and Improved Apparatus for Cutting Valve Faces, of which the following is a full, clear, and exact description.

This invention relates to valve cutting devices and contemplates broadly an apparatus for cutting the face of a valve for refinishing the surface, after the same has become worn, pitted or otherwise mutilated to such an extent as to hinder the perfect seating and functioning of the same.

Some of the principal objects of the present invention reside in the provision of an apparatus which includes means for supporting and rotating a valve in the presence of a cutting tool; means for rendering the same adjustable to accommodate valves and valve stems of various sizes; means for adjusting the cutting tool with respect to the valve for obtaining various angular cuts of the valve face; and means for varying or regulating the pressure of the valve against the cutting tool whereby to obtain a finer or coarser cut.

Further objects of the invention reside in the simplicity of the construction, operation and method of association or removal of the valve from the apparatus.

With the above recited and other objects in view, some of which will appear more clearly hereafter, reference is had to the following description, the appended claims and the accompanying drawings forming a part of this application, and in which;

Figure 1 is a plan view of the apparatus. Figure 2 is a transverse sectional view therethrough taken approximately on the line 2—2 of Figure 1.

Figure 3 is a fragmentary sectional view taken on the line 3—3 of Figure 1.

Referring to the drawings by characters of reference, 10 designates the base of the apparatus which may be cast or otherwise constructed and which is provided with spaced upstanding aligned bearing blocks 11 having V-shaped notches or recesses 12 in their upper surfaces which are adapted to receive the valve stem S of a valve V. The blocks 11 are arranged adjacent one corner of the base as illustrated. A standard 13 is provided on the base to one side of the blocks 11 and medially of the same to constitute a

fulcrum and support for one end of the retaining yoke 14. The opposite end of the retaining yoke 14 is forked to provide the spaced arms 15 which are adapted to overly the bearing blocks 11. The retaining yoke is provided with a vertically arranged enlarged aperture which receives the upstanding shank 16 having a threaded extremity 17 for the reception of a securing nut 18. By this arrangement the stem S of a valve placed in the V-shaped notches or bearings 12 of the blocks 11 may be confined therein against removal. An upstanding tool block 19 is provided substantially at the center of the base and is angularly disposed with respect to the sides and ends thereof. The tool block is formed adjacent one side thereof with an upstanding flange 20. The cutting tool 21 is apertured as at 22 for the reception of a securing screw 23 which is passed therethrough and threadedly engaged in the threaded bore 24 extending downwardly through the upper end of the tool block. The forward face of the tool is beveled to provide the cutting edge 25 and the rear face is oppositely beveled as at 26 to coact with the adjusting screws 27 which are threadedly received by the flange 20. By this arrangement the cutting tool may be adjusted to obtain various angular cuts of the valve face. In order to provide means for regulating and obtaining an even depth of the cut, a pressure regulating screw 28 is provided which is threaded through the upstanding lug 29 disposed at the opposite end of the base from the bearing blocks 11. The screw 28 is arranged in axial alignment with the valve and its inner end bears directly on the crown or head of the valve as clearly illustrated in Figure 1 of the drawings. The opposite end of the screw is provided with a knurled knob 30 for manipulating the screw to obtain the desired adjustment thereof. In order to provide means for rotating the valve, use is made of a crank 31 which is provided with a handle 32 at one extremity and is formed with an opening 33 at its opposite extremity which is adapted to receive the valve stem. A set screw 34 serves to secure the crank to the valve stem. In use and operation of the device, the valve stem S is arranged in the V-shaped bearings or notches 12 of the bearing blocks 11 with the valve proper disposed between the lug 29 and one of the blocks 11, the securing screw 23 is loosened to obtain the

proper angular adjustment of the cutting edge with respect to the valve by manipulating the screws 27; the securing screw 23 is then manipulated to clamp the tool against 5 accidental displacement. After the desired adjustment of the tool is obtained, the pressure regulating screw 28 is manipulated to obtain the desired depth cut to be obtained and the crank 31 is attached and rotated. 10 The retaining yoke 14 co-acts with the bearing notches 12 to receive various diameters of valve stems and longitudinal shifting of the stem within the notches will permit of the use of various sizes of valves in connection with the apparatus. 15

While there has been illustrated and described a single and preferred embodiment of the invention no limitation is necessarily made to the precise structural details, as it 20 is understood that variations and modifications which fall within the scope of the appended claims may be resorted to when found expedient.

I claim:

25 1. A device for refacing gas engine valves including a base, means for supporting the valve comprising longitudinally spaced bearing standards provided with aligned V-shaped notches in the upper ends, a laterally spaced intermediate standard on said base, a stud bolt intermediate said standards, a yoke having spaced arms projecting in one direction and a central arm projecting in the opposite direction and provided with a 30 central aperture receiving the stud bolt, the said spaced arms adapted to overlie the bearing standard to confine the valve stem in the V-shaped notches thereof for turning movement, the single arm being ful- 35 crumed on the remaining standard and a nut for advancing and retaining the yoke against said standard and valve stem, a tool supporting means comprising an up- 40 standing tool support, a tool swivelly

mounted on the support and adjusting and 45 retaining means for holding the tool in various angular positions, and means for regulating the pressure of the valve face against the tool comprising a bearing standard and a pressure regulating screw extending there- 50 through in axial alignment with the valve for engaging the side of the valve opposite to that from which the stem projects.

2. An apparatus for refacing valves including a base having longitudinally spaced 55 upstanding bearing blocks having V-shaped grooves in their upper ends, said grooves disposed in horizontal and vertical alignment for the reception of a valve stem, a laterally spaced standard longitudinally intermediate of said bearing blocks, an upstanding stud bolt between the standard and bearing blocks, an apertured yoke received by the upper end of the stud bolt having spaced extremities overlying the V-shaped 60 notches and an oppositely projecting lateral extremity in engagement with the upper end of the standard, a retaining nut 65 threaded on the upper end of the stud bolt for advancing and retaining the spaced extremities of the yoke and in engagement with the stem and the laterally spaced extremity in engagement with the standard, an upstanding tool block on the base spaced laterally out of axial alignment with the 70 V-shaped notches, a cutting tool carried by the tool block, means for varying the angle of the cutting edge of the tool and retaining the same in its adjusted position, an up- 75 standing lug having a threaded bore in axial alignment with the V-shaped notches, and a pressure regulating screw in the bore of said lug adapted to engage with a valve for advancing and retaining the face there- 80 of into coating engagement with the cut- 85 ing edge of the tool.

EARL BLAINE SHERK.
